LEG-BRACING MEANS FOR BED-FRAMES.

1,071,927.

Specification of Letters Patent.

Patented Sept. 2, 1913.

Original application filed October 14, 1912, Serial No. 725,620. Divided and this application filed January 6, 1913. Serial No. 740,431.

To all whom it may concern:

Be it known that I, ADOLPH C. KLOPPING, a citizen of the United States, and a resident of Toledo, in the county of Lucas and State of Ohio, have invented a certain new and useful Leg - Bracing Means for Bed-Frames; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to bed davenports, and is a division of the application for United States Letters Patent filed by me on October 14, 1912, Serial No. 725,620.

The object of my invention is the provision of improved means for transversely bracing the folding supporting legs at the outer end of the bed-frames of apparatus of this character, whereby to facilitate the folding and unfolding movements of the legs relative to the frame and to obviate objections incident to the use of the types of leg-bracing means heretofore employed.

The invention is fully described in the following specification, and while, in its broader aspect, it is capable of embodiment in numerous forms, a preferred embodiment thereof is illustrated in the accompanying drawings, in which,—

Figure 1 is an end elevation of the davenport frame with the back and one end thereof removed, the seat frame being in vertical cross-section, and the bed-frame partly unfolded, with the complete unfolded position thereof shown in dotted lines. Fig. 2 is an outer end view of the bed-frame in unfolded position, with a part broken away, and Figs. 3 and 4 are different enlarged details of portions of the leg bracing means and the manner of connecting them to the frame.

Referring to the drawings, 1 designates the outer section of a bed-frame, such section, in the present instance, having its sides connected at their inner ends to the adjacent ends of the sides of the adjoining bed-frame section 2 by links 3, which links are pivotally connected to the respective sec-

tions to permit a folding of the outer section 1 in spaced relation over the section 2, as indicated in full lines in Fig. 1.

A supporting leg 4 is pivoted at its upper end to each side of the bed-frame section 1 adjacent to the outer end thereof for longitudinal folding movements relative thereto. These legs coöperate, in the present instance, with a set of legs 5 which are pivoted to the sides of the section 2 at the forward ends thereof, and also with a seat 6 in supporting the bed-frame in a suitable manner, as is well understood in the art. The legs 4 are preferably of angle-iron form in cross-section to adapt the inturned flange of each to rest against the under side of the frame section when folded thereagainst, with the flange thereof which projects longitudinally of the bed-frame lapsing the outer side of the frame section, as shown in the full line position in Fig. 1.

Each of the legs 4 is braced transversely of the section 1 by a brace-bar 7, which is secured at one end to a leg preferably adjacent to its lower end, as at 8, and has its opposite end hinged to the outer end or cross-piece of the section 1 for longitudinal swinging movements relative thereto, thus enabling the leg and brace to have free folding movements relative to the frame. The hinge connection between the cross-piece of the frame and each brace is shown as comprising a strip 9, which is bent in substantially U-shape with its loop portion projecting loosely through a registering slot 10 in the inner end of the brace-bar to permit such parts to have free relative pivotal movements, and with its legs straddling the rearwardly projecting flange 11 at the lower inner edge of the cross-piece of the section 1 and riveted or otherwise rigidly secured thereto.

It will be noted that the brace-bars are attached at their outer ends to the outer or front sides of the respective legs 4 and that they are attached to the loop members 9 at points below and slightly to the rear of the leg pivots (the position of which is indicated at 4' in Fig. 4) and to the rear of the vertical plane of attachment of the bars to the legs when the legs are in the unfolded position shown in Fig. 1. It is found in practice that the legs and braces are capable of free and easy folding or unfolding

movements relative to the frame when connected thereto in this manner. It is also found that this manner of separately bracing the legs 4 relative to the frame enables them to have relative folding or unfolding movements without the binding tendency which is present in the use of the leg bracing means heretofore employed in like connections.

10 Pivoted to each leg 4 adjacent to its pivot, as at 12, is an arm 13 which is provided with a longitudinally extending cam slot 14 that works over the guide pin 15 attached to the associated side of the frame section 1 adjacent to the outer end thereof and coöperates with such pin to lock the leg in its set up position when the frame is unfolded. The outer or free end of the arm 13 is provided with a hook 17 adapted to have engagement with a pin 18 on the associated side of the frame section 2 when the attached leg 4 is folded against the frame section 1 and such section is in its folded position over the section 2. When the parts 15 are in this position and the legs 4 are pulled upward from their reclining or folded position against the section 1 the cam slot 13 and pin 15 coöperate with the leg to throw the hooked end thereof from engagement 20 with the pin 18 to permit an unfolding of the frame section 1 from over the section 2, as is more fully described in my said application Serial No. 725,620.

One of the main reasons for connecting 25 the leg brace 7 to the outer end of the frame section 1 in the manner above described is to facilitate a free movement of either leg 4 from its folded position relative to the section 1 to release the catch arm 13 from engagement with the pin 18 and to eliminate 30 any tendency of the leg bracing means to cause a binding action of a leg during an unfolding movement thereof unless both legs are moved in unison and no inward 35 strain is applied thereto during the unfolding operation.

I wish it understood that my invention is not limited to any specific construction or arrangement of the parts except in so far 40 as such limitations are specified in the claims.

Having thus described my invention, what I claim as new, and desire to secure by Letters Patent, is,

55 1. In combination, a bed-frame having side and cross-bars, a supporting leg pivoted to said bed-frame for folding movements relative thereto, and a brace member projecting from said leg in the direction of 60 projection of the pivotal axis of the leg and

having its outer end portion hinged to a cross-bar of the bed-frame to permit the leg and brace to have pivotal swinging movements together relative to the bed-frame in a direction which is transverse to the direction of projection of the brace from the leg, the axes of the leg and outer end of the brace being out of alinement.

2. In combination, a bed-frame having a cross-piece at its outer end, a member fastened to said cross-piece and forming a pivot loop with its opening disposed transversely of the frame, a leg pivoted to one side of the bed-frame for swinging movements longitudinally of the frame with its swinging axis out of alinement with said pivot loop, and a brace-bar attached at one end to said leg and extending inwardly therefrom transversely to the bed-frame in diagonal relation to the leg and having its inner end in hinged connection with said loop member.

3. In combination, a folding bed-frame having a cross-piece at its outer end provided with an inwardly projecting flange, a member fastened to said flange and forming a pivot loop with its opening disposed transversely of the frame, a supporting leg hingedly carried by the frame at one side of said member for folding movements against the frame longitudinally thereof, a brace-bar attached at one end to said leg and extending inwardly therefrom transversely of the bed-frame in diagonal relation to the leg and having its inner end provided with an eye through which the loop of said member freely passes to hingedly connect said member and bar.

4. In combination, a folding bed-frame having a cross-piece at the outer end thereof, a member secured to said cross-piece and forming a pivot loop with its opening disposed transversely of the frame, a leg pivoted to one side of said frame with its pivot disposed above and forwardly from the axis of said member loop, and a brace-bar attached at one end to said leg and extending inwardly therefrom transversely of the bed-frame in diagonal relation to the leg and having its inner end in link engagement with said member loop to permit said bar to have pivotal movements with the leg relative to the bed-frame.

In testimony whereof, I have hereunto signed my name to this specification in the presence of two subscribing witnesses.

ADOLPH C. KLOPPING.
